The ornamental design for a dual sided adhesive heel pad, as shown and described.

DESCRIPTION

FIG. 1 is an upper perspective view of the dual sided adhesive heel pad showing my design.

FIG. 2 is a top plan view thereof,

FIG. 3 is a bottom plan view thereof;

FIG. 4 is a front elevation view thereof;

FIG. 5 is a back elevation view thereof;

FIG. 6 is a side elevation view thereof;

FIG. 7 is an opposite side elevation view thereof; and,

FIG. 8 is another perspective view thereof, showing installation inside a shoe in broken lines.

The broken line features are presented for illustrative purpose and form no part of the claimed design.

The pattern on the front surface in FIGS. 1 and 2-8 represents a first adhesive.

The pattern on the back surface in FIGS. 3 and 8 represents a second adhesive.
